UNITED STATES PATENT OFFICE.

FELIX J. BENITO, OF TAMPA, FLORIDA, ASSIGNOR TO NEW YORK SIGNAL CO., INC., OF NEW YORK, N. Y.

VEHICLE-SIGNAL.

1,273,990.

Specification of Letters Patent. Patented July 30, 1918.

Application filed June 27, 1917. Serial No. 177,316.

To all whom it may concern:

Be it known that I, FELIX J. BENITO, a citizen of Spain, residing at Tampa, in the county of Hillsborough and State of Florida, have invented a new and useful Vehicle-Signal, of which the following is a specification.

The present invention relates to vehicle signals, and is particularly an improvement over the vehicle signal disclosed in my co-pending application, Serial Number 167,358, filed May 8, 1917.

The invention resides in the provision of novel actuating means and improved features of construction, to enhance the utility and efficiency of the signal.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawings, wherein:

Figure 1 is a plan view of the signal device, the actuating mechanism not being shown.

Fig. 2 is an elevation of the complete device, portions being broken away and others shown in section.

Fig. 3 is a sectional view on the line 3—3 of Fig. 2.

Fig. 4 is a sectional detail of the pedal operated means.

Fig. 5 is a detail view of a holder for the flexible wire tubing.

Fig. 6 is a plan view of a modified form of clamp bracket.

Fig. 7 is a longitudinal section of a modified form of spring means for the actuating wire.

Fig. 8 is a detail view of a modified form of spring.

The signal member arm 1 is of lazy tong construction, embodying crossed pivoted levers connected by eyelets 2, and the arm is provided at its free end with a link 3 in the form of an index carrying a lamp socket 4 fitted within a recess 5 in the index, said recess providing resilient prongs

6 fitting opposite sides of the socket 4 and having lugs or teeth 7 to engage the socket and hold it in place. The socket 4 holds a removable lamp bulb 8, one terminal of the bulb being grounded by way of the socket 4 and arm 1, while the other terminal of the bulb is connected through the medium of the socket 4 with an insulated conductor 9' threaded back and forth through the eyelets 2. The bulb 8 can be lighted during darkness, and will be projected and retracted with the index 3 when the arm 1 is extended and contracted.

An open ended casing 9 of sheet metal or other suitable material is provided for receiving and housing the arm 1 when it is contracted, and one end of the casing 9 is supported by a head 10, having the portion 11 fitted within the end of the casing, said casing being secured to the portion 11 by means of screws 12 or the like. The head 10 has a vertical flange 13 projecting within the casing 9 for supporting the arm 1. One lever of the arm 1 at the basal end thereof is pivoted, as at 14, to the flange 13 at one side near the lower end thereof, and the other lever of the arm 1 at the basal end thereof is pivotally and slidably connected to the flange 13 by means of a vertical rod 15 at one side of the flange 13 having at its upper end a finger 15^a extending at an angle through said lever and through a vertical longitudinal slot 16 with which the flange 13 is provided. The finger 15^a thus serves as a pivot for the respective lever, and is movable vertically for extending and contracting the arm. Cast integral with the head 10 and its flange 13 is a thickened portion 16' having a vertical bore 17 therein receiving a coiled wire expansion spring 18 which surrounds the rod 15 and bears against the finger 15^a, whereby to raise said finger and contract the arm 1 when free to do so. An actuating wire or other flexible element 19 has one end connected to the lower end of the rod 15 within the spring 18 and extends slidably through a plug 20 extending upwardly through the bottom of the casing 9 and threadedly engaging the lower end of the portion 16 below the bore 17. Attached to the plug 20 by means of solder or otherwise, is a coiled wire tube or guide 21 for the actuating wire 19 through which the latter wire extends slidably, in order that

when the wire 19 is pulled, this will pull the rod 15 downwardly, to extend the arm 1 for signaling purposes, and when the wire 19 is released, the spring 18 in recoiling or expanding, will contract the arm.

In order to support the device, there is provided a clamp bracket 22 to engage the wind shield or other object (Fig. 6 shows a modified form of bracket 22' having differently shaped jaws), and the bracket 22 has a stud 23 supporting a bracket arm 24 provided with a clamp 25 at one end embracing the stud 23 to enable the arm 24 to be adjusted about the vertical axis of the stud. 10 The arm 24 is provided at its other end with a clamp 26 at right angles with the clamp 25 and embracing outstanding shank 27 with which the head 10 is provided, in order that the casing and signal arm can be adjusted 15 about a horizontal axis. 20

It is preferable and desirable to provide a mirror 28 attached to the rear side of the casing 9, in order that the operator can observe in the mirror, vehicles in rear, while 25 the front side of the casing can be used for supporting an electric lamp 29 to provide a spot- or search-light.

The electrical connections for the lamp or bulb 8 and lamp 29 embody a plate or 30 piece 30 of insulating material fitted against one side of the casing within the same at one side of the flange 13, and a leaf spring contact 31 is fastened to the insulation 30 by means of a bolt 32 or otherwise, said leaf 35 spring 31 and its securing means being insulated from the casing. The insulation 30 is preferably secured to the side of the casing by means of eyelets 33, the conductor 9' extending outwardly through one of the eyelets. Another conductor 34 extends through 40 another eyelet and is fastened to the contact 31. A conductor 35 is connected to the lamp 29, and a conductor 36 connects said lamp with the spring contact 31, and extends 45 through the third eyelet 33. The conductors 9', 34 and 35 are connected to the source of electrical energy and controlling switches (not shown). When the circuit of conductors 34 and 35 is closed, this will light the 50 lamp 29, the conductor 34 being the feed wire, and when the rod 15 is moved downwardly to project the signal member, the finger 15' will brush against the spring contact 31, and close the circuit of the bulb or lamp 55 8 to render the signal effective when it is dark.

The actuating means embodies a tubular post or guide 37 having its lower end threaded or otherwise secured to a boss of a base 60 plate 38 which can be secured by means of screws or otherwise to the dash or foot-board of the automobile to hold the post 37 in place adjacent to the brake pedal P. A cap 39 is threaded or otherwise engaged 65 upon the upper end of the post 37 and has

attached thereto, a removable screw plug 40 to which the lower end of the tube 21 is secured, the wire 19 extending slidably through the plug 40 into the post 37. The post 37 has a longitudinal slot 41 through 70 which an operating member or follower 42 extends under the pedal P. The member 42 is threaded or otherwise secured to the upper end of a guide rod 43 arranged within the post 37 and sliding through the base 75 plate 38. A coiled wire elastic spring 44 has its ends attached to the upper end of the rod 43 and end of the wire 19. The spring 44 is of such construction that when the member 42 is started downward, the spring 80 will pull the wire 19 thereby to extend the signal arm immediately, and after the arm has been extended, the spring 44 is capable of being stretched, to permit of the further movement of the member 42 with the pedal 85 P. The pedal P can, therefore, be used to operate the signal member since the first part of the movement of the pedal serves to operate the member 42 sufficiently to extend the signal arm, the remainder of the movement of the member 42 with the pedal simply stretching the spring 44. The member 90 42 can be used as a pedal in some cases, to be operated by the foot, for extending the signal arm at will. A spring 42' raises member 42.

A holder for the tube 21 can be employed, the same embodying a U-shaped clamp member 45 to straddle an edge of the dash or other supporting member, and a clamp 46 embraces the tube 21 between its ends, and serves to support it, said clamp 46 being secured to the member 45 by means of a screw 47 or other suitable means. A clamping screw 48 is threaded through the other limb of the member 45 to clamp it to the dash or supporting member. The screw 47 when tightened clamps the clamp 46 tightly against the member 45, the screw 47 being readily engaged by a screw driver inserted 100 through the aperture of the member 45 when the screw 48 is removed.

In Fig. 7 a modified form of spring means for the actuating means is shown. Thus, there is provided a tubular member 37' having the caps 38' and 39' at its ends, the tube 21 being secured to the cap 39', and a rod or wire 43' sliding through the cap 38' and having a hook or other means 42' to be connected to the brake pedal or other operating member. The coil elastic spring 44' is disposed within the tubular member 37' and connects the wire 19 with the rod 43', there being a flexible joint between the spring and rod 43'. As shown in Fig. 8, the elastic spring 44'' has one end extended longitudinally to provide an integral actuating rod 43'' having the hook 42'' or other means of connecting it to the pedal or actuating member. 115 120 125 130

Having thus described the invention, what is claimed as new is:

1. A device of the character described, embodying a head, a lazy tong signal arm having levers, one lever being pivoted to the head, a rod engaging another lever of the arm and slidably engaging the head, an expansion spring surrounding said rod and confined between the head and the last mentioned lever to contract the arm, a flexible tubing connected to the head, and an actuating wire extending through said tube and spring and connected to the rod.

2. A device of the character described, embodying a head, a movable signal member carried thereby, an actuating member, a flexible wire connected to the signal member, an elastic spring between said wire and actuating member, and a tube in which the wire is slidale.

3. A device of the character described, embodying a head, a movable signal member carried thereby, a tubular member, a tube connected to said member and extending to the head, a flexible wire extending through said tube and connected to the signal member, an actuating member movable within the tubular member and extending therefrom, and an elastic spring within the tubu-

lar member connecting the actuating member and wire.

4. A device of the character described, embodying a head, a movable signal member carried thereby, a tube, actuating means connected to the tube and including wire extending through the tube and connected to the signal member, a supporting member, and means carried by the supporting member for supporting the tube between its ends.

5. A device of the character described, embodying a head, a movable signal member carried thereby, a tube extending to the head, actuating means to which the tube is connected and including a flexible wire extending through the tube and connected to the signal member, a U-shaped member, a clamp for the tube, means for securing said clamp to said member, and a clamping screw carried by said member opposite to the last mentioned means.

In testimony that I claim the foregoing as my own, I have hereto affixed my signature in the presence of two witnesses.

FELIX J. BENITO A.
